PHOTO-ELECTRIC TUBE

Application filed December 7, 1928, Serial No. 324,470, and in Germany December 9, 1927.

Our invention relates to photo-electric tubes of the kind comprising a sealed tube which may be of glass, quartz or other suitable material and containing a film electrode 5 of light sensitive material (e. g., potassium, sodium or the like) and a second electrode for collecting the electrons emitted by the film electrode when the latter is subjected to the influence of light.

10 More definitely stated, the object of our invention is a photo-electric tube particularly adapted for attachment to various apparatus where only narrow spaces, crevices or channels are left for the insertion of the photo-electric tube. The photo-electric tube disclosed in this case is of such structure as to require extremely small space. This is, generally speaking, achieved by arranging the electrodes on one side and all terminals on the other side of the tube and opposite the side from which the light rays fall on the tube. It is possible in this way to construct a very small and efficient tube which may be inserted into small space in an apparatus 15 where the tube is required, being attached to the apparatus not unlike the human eye is attached to the head, and the light rays will fall on the tube without obstruction since all terminals are provided collectively in the 20 rear of the tube. It will be obvious that such structure of a photo-electric tube will be very valuable in many cases. The usual photo-electric tubes have terminals arranged separately in a certain angle to each other 25 and require a relatively large space. Thus, by collectively arranging the electrodes on one side (where the light is received) and by collectively arranging the terminals on the opposite side, we succeeded to provide a 30 photo-electric tube of great utility not disclosed in any prior invention.

Our invention will be best understood by reference to the following description which should be read in connection with the accompanying drawing.

In this drawing,

Figure 1 represents a diagrammatic view of a photo-electric tube, the light sensitive film of which is produced by pouring the

photo-electric material in liquid condition into the tube.

Figure 2 represents a diagrammatic view of a photo-electric tube, the light sensitive film of which is produced by pouring the photo-electric material upon a plate provided in the interior of the tube and carrying a 55 tight meshy metallic net.

Figure 3 represents a diagrammatic view of a photo-electric tube, the light sensitive film of which is produced by precipitating the photo-electric material in vaporized condition upon a recess in the walls of the tube which rises centrally into the tube.

Referring particularly to Figure 1, the 60 tube 1 contains an anode electrode 2 and a cathode light sensitive film 3. The light rays strike the tube in the direction of the arrows 4. Both of the terminal wires 5 and 6 of the cathode light sensitive film and of 65 the anode member, respectively, are arranged on the same side of the tube and opposite to the side exposed to the light rays.

It will be appreciated that the structure described above possesses many advantages 70 over photo-electric tubes known at the present time, which are usually provided with a separate lateral stalk containing the anode terminal wire. Consequently, the space required by these photo-electric tubes must be 75 relatively large. The advantages of our invention will be very valuable in many cases.

As shown in Figure 1, the tube 1 is provided with a conduit 7 for supporting in its interior the anode terminal. This conduit 80 is also arranged on the tube opposite the side exposed to the light rays. The conduit 7 is adapted to be heated after the light sensitive film is positioned in the tube, and this heating can be accomplished without heating the light sensitive film. All precipitates 85 can, therefore, be easily removed and a sufficient insulating portion is produced in the interior of the tube. The conduit 7 extends 90 into the interior of the tube beyond the film 3, in order to prevent the liquid photo-electric material from entering the conduit 7 during the manufacturing process when applying the liquid material to form the film.

Referring to Figure 2, the light sensitive 95

film is in this case applied to a supporting plate 9. The plate is for this purpose provided with a tight meshy net 10 of copper, silver or another metal, adapted to receive and to absorb the liquid photo-electric material. When the liquid photo-electric material is brought in contact with the net 10, this net will receive and will absorb the material owing to cohesion and capillary attraction, and will be uniformly coated with a tight light sensitive film.

An especial advantage of the last described photo-electric tube resides in the fact that very small quantities of photo-electric material are required and that the material is applied in liquid (and not in vaporized condition). The possibility of inconveniences which may be caused by undesirable precipitates of vaporized photo-electric material as usually applied, is, consequently appreciably reduced.

Referring to Figure 3, the tube 1 is provided with a recess 11, rising centrally into the interior of the tube. Opposite the top 25 of the recess 11, within the tube, there is arranged a rough meshy net 12 of metal, closely attached to the interior surface of the front portion of the tube and connected to the anode terminal wire 6. The net 12 serves as anode electrode. The light sensitive film is applied to the top of the recess 11 within the tube by feeding the photo-electric material in vaporized state into the tube and by simultaneously heating the outer wall of the tube and cooling 35 the recess 11 by a current of cold air or in another suitable manner. Numeral 13 designates a suitable base.

Some of the advantages of the last described embodiment of our invention reside in the fact that extremely small quantities of photo-electric material are required for producing the light sensitive film and that the tube may be easily and safely manufactured by ordinary labor without requiring experts. 45 This is due to the peculiar method in which the vaporized material is applied to the walls of the recess by cooling the same while heating the remainder of the tube. Obviously, the vaporized material will only precipitate 50 on the cooled recess without any other provision, and this work can be performed easily and safely.

Numerous changes can, of course, be made in the structure and in the arrangement of 55 details of our invention without departing from its spirit. We, therefore, want to have it understood that we desire to apply the invention only subject to the limitations as expressed in the claims which follow:

60 1. A photo-electric tube having a sealed envelope; a light sensitive cathode; an anode electrode positioned within said envelope in the end to be exposed to the light rays; a terminal connected to said cathode; a terminal connected to said anode electrode; and

a conduit extending into said envelope through said cathode and separately mounting said anode terminal.

2. A photo-electric tube comprising a sealed envelope; a light sensitive cathode electrode to be exposed to light rays received from one side of said tube; an anode electrode; a terminal connected to said cathode electrode; and a terminal connected to said anode electrode, said last mentioned terminal extending through said envelope through an opening in said cathode electrode and through the side of said envelope opposite said one side.

3. A photo-electric tube comprising a sealed envelope having a flat window; a light sensitive cathode electrode; an anode electrode; a terminal connected to said cathode electrode; a terminal connected to said anode electrode, said last mentioned terminal extending into said envelope through an opening in said cathode electrode, said cathode and anode electrodes being parallel to said window, and said anode and cathode terminals extending into said envelope on the side opposite said window.

4. A photo-electric tube comprising a sealed envelope having a window; a light sensitive cathode electrode; an anode electrode; a terminal connected to said cathode electrode; a terminal connected to said anode electrode; said terminals projecting through the sides of said envelope opposite said windows and said electrodes being interposed between said windows and the side through which said terminals project and extending at right angles to the path of the beam of light whereby substantially all the light entering from said window is impinged upon and absorbed by said cathode electrode.

In testimony whereof we affix our signatures.

HEINRICH H. GEFFCKEN.
HANS R. RICHTER.
